UNITED STATES PATENT OFFICE.

JOHAN EDWARD GAMALIELSON, OF KAUMANA, TERRITORY OF HAWAII.

CABLE-SUPPORT.

SPECIFICATION forming part of Letters Patent No. 707,314, dated August 19, 1902.

Application filed August 24, 1901. Serial No. 73,141. (No model.)

To all whom it may concern:

Be it known that I, JOHAN EDWARD GAMALIELSON, a citizen of the United States, residing at Kaumana, in the district of Hilo, Territory of Hawaii, have invented certain new and useful Improvements in Cable-Supports; and I do hereby declare that the following is a full, clear, and exact description of the invention, which will enable others skilled in the art to 10 which it appertains to make and use the same.

Figure 1 is a plan view of my improved cable-support, and Fig. 2 is a front elevation thereof. Fig. 3 is a side elevation from the right of Figs. 1 and 2. Fig. 4 is a perspective view of the cable-supporting head.

As thus shown and described, the invention consists in a device for securely holding a wire cable A to its supporting-posts, (not shown,) whereby said cable is supported 20 above ground for transportation purposes—as, for instance, the transportation of sugar-cane from the cane-fields to the sugar-mill some distance away, and for which purpose the invention is extensively used. Hitherto 25 in the use of cables for this and other transportation purposes there has been constant annoyance from the slipping down of the cable from its supporting-posts, and this has entailed much additional labor and incon- 30 venience in the operation of a plant. By my construction this difficulty is wholly overcome and remedied, and the sheave which carries the load is enabled to pass without obstruction.

To these several ends I employ a suitable head B, which serves as a support or carrier for the cable and which has the peculiar shape shown in Fig. 4. As here shown, said head has a circular hole 2 through the center of its 40 head portion proper and longitudinal grooves 3 in the opposite edges thereof for the cable to lie in, while its integral projecting portion 4 is narrower somewhat than the main head portion having said grooves and is equipped 45 with a clip or yoke C, engaged over cable A and firmly secured by pins 5 and keys 6 through said head. Threaded bolts would serve the same purpose. The clip or yoke C presses the cable-head upon the flat edge of the head 50 projection 4 and holds it securely there, while the groove 3 confines the cable over and upon the main portion of the said head. The cor-

ners of the head are rounded off at b and b to prevent chafing on the cable.

D is an arm having a cylindrical projection 55 d, on which hole 2 in head B is engaged and wherein the engagement is free enough to permit rocking of the head. This arm is constructed with holes to fasten it firmly to a post, from which it projects laterally far 60 enough to get the desired clearance for the passing load. Headpiece B can be reversed, so as to enable it to be worked right or left, and the projection 4 is always in the direction of the approaching load. My method of 65 supporting the head on arm D permits the head to play or turn thereon and the cable to vibrate, as against other devices that I have seen which hold the cable rigidly, thereby causing it to wear off at the point of contact 70 in a very short time. This made transportation by cable very expensive.

What I claim for my invention is a device capable of holding a wire cable very securely to its supporting-posts when suspended above 75 the ground for transportation purposes without obstructing the passage of the load or the sheave carrying the load, and being made on the eccentric principle it gives sufficient play to the cable to allow the same to vibrate 80 when in use. At the same time it is so simple that it cannot get out of order and so strong and compact as to be almost unbreakable. This contrasts very decidedly with devices I have seen with special means to allow 85 for vibration of the cable and which the weight of the load and the vibration of the cable would cause to slip apart, and after having been put on again repeatedly would fail altogether to hold the cable and become useless. 90

What I claim is—

1. A support for cables comprising a head with a grooved edge lengthwise and a central opening for a support, and provided with an extension at one end, a cable resting on the 95 upper edge of the head and extension and a clip over the cable locked on the extension and confining the cable on said support, substantially as described.

2. A supporting-head for cables having a 100 head with a central hole and an arm in said hole on which the head is loosely mounted, said head having grooves lengthwise in its opposite edges and adapted to be reversed, and

provided with an extension at one end constructed to receive a clip for confining a cable on said head, substantially as described.

3. The combination of the supporting-arm, 5 the head rotatably mounted thereon at its center and having an extension at one end, a cable resting on the upper edge of the head and its extension and a clip engaged over the

cable and the said extension and holding the cable in place, substantially as described. 10

Witness my hand to the foregoing specification this 6th day of July, 1901.

JOHAN EDWARD GAMALIELSON.
